CLOSURE

Thomas R. Curran, Monroeville, Pa., assignor to Mine Safety Appliances Company, Pittsburgh, Pa., a corporation of Pennsylvania

Filed Dec. 16, 1964, Ser. No. 418,621
4 Claims. (Cl. 220—27)

This invention relates to breakaway container closures and more particularly to breakaway closures for containers having a flanged neck opening.

Closures of this type are generally made of metal and utilize a flared skirt designed to be crimped over the flange of the container neck and having a tab to tear away a strip of metal. Besides requiring the utilization of an accessory tool to perform the crimping operation, such closures are not entirely satisfactory for quick removal since the metal parts crimped over the flange must be bent to free the closure from the flange and hands are easily lacerated by the sharp torn edges of the metal. Simple, fast and safe breakaway closures are especially desirable in emergency equipment, such as gas mask canisters.

It is an object of this invention to provide a closure that can be secured in position without the use of tools, which may be used with an appropriate gasket to effectuate a gas tight seal or which may be used as a secondary closure to protect an inner frangible seal. Another object is to provide such a closure that can be simply and rapidly removed with complete safety to the operator.

With the above and other objects in view, the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification:

FIGURE 1 is a bottom view of the cap member of a closure constructed in accordance with the invention;

FIGURE 2 is a cross-sectional view of the cap member taken on the line 2—2 of FIGURE 1;

FIGURE 3 is a top view of the clip, for use with the cap member of FIGURE 1;

FIGURE 4 is a side view of the clip of FIGURE 3;

FIGURE 5 is a top view of the closure consisting of the aforesaid cap member and clip in position on a container; and

FIGURE 6 is a cross-sectional view of the closure taken on the line 6—6 of FIGURE 5.

Referring now to the drawings in which like characters of reference designate similar parts in the various views, the molded cap member 9 has an integral flat top wall 10 and a circular side wall 14 adapted to fit snugly over and seal against the flange 20 of a container 21, such as a gas mask canister. Notches 15 and 15', positioned at diametrically opposite points in the side wall 14 and between ribs 12 and 13 and 12' and 13' respectively, extend through the side wall 14 to the bottom surface of the top wall and terminate in a groove 16 that extends between the notches and across the bottom surface of the top wall. An outwardly extending integral lifting lip 11 is positioned normal to the groove 16, preferably having an integral skirt 22. A sealing disc or gasket 19 may be positioned in the cap member to effectuate a seal between the cap member 9 and the container flange 20. The molded clip 17, having as integral parts a concave bar spring 18 and hooks 23 and 23' on each end thereof, is positioned under tension over the top of the cap member 9. One edge of the bar spring 18 is positioned and maintained in alignment with the groove 16 by hooks 23 and 23' fitting snugly between the ribs 12 and 13 and 12' and 13' respec-

2

tively. The hooks extend under the cap member side wall 14 and the container flange 20 thereby sealing the cap against the container flange 20. When so positioned the clip 17 exerts spring tension across the top of the cap member 9, holding it rigidly in position, and causing it to bear and seal against the container flange 20 through the entire circumferential surface contact of the sealing disc 19 with the container flange 20. Thus a complete protective seal is effectuated as shown in FIGURE 6.

To rapidly and safely remove the closure, finger pressure is exerted in an upward direction on lip 11 causing cap member 9 to break along groove 16, the edge of the bar spring 18 acting as a bearing surface. The portion of the cap member including the lip is thus flipped off and the remaining portion of the cap member 9 and the clip 17 fall away from or may be easily slid off the container.

The cap member is molded from a synthetic resin which is sufficiently brittle to break easily and cleanly, and the clip member is molded from synthetic resin that is sufficiently resilient to act as a spring; a great variety of synthetic resins are well known and suitable for use in the cap or clip and several are sufficiently brittle and sufficiently resilient that they can be used for both the cap and clip, such as styrene, medium impact styrene, cellulose acetate, styrene acrylonitrile and acrylic.

I claim:

1. A breakaway closure for a container having a flanged neck opening comprising

a brittle cup-shaped cap member adapted to fit over the container flange having a flat top wall and a downwardly extending circular side wall, said side wall being divided into two portions by diametrically opposed notches,

a clip fitting over said cap member comprising a concave bar spring having two ends and a downwardly and inwardly extending hook integrally formed on each end of said bar spring, said hooks adapted to engage the container flange when said bar spring is under tension,

a plurality of ribs on said side wall maintaining the cap member and clip in fixed angular relation wherein one edge of said bar spring is in alignment with said notches,

an outwardly extending lip integral with said cap member normal to and opposite said bar spring edge, whereby an upward pressure exerted on said lip will break said cap member along said bar spring edge.

2. A breakaway closure for a container having a flanged neck opening comprising

a brittle cup-shaped cap member adapted to fit over the container flange having a flat top wall and a downwardly extending circular side wall, said side wall being divided into two portions by diametrically opposed notches, a groove in the bottom surface of said top wall extending between said notches,

a clip fitting over said cap member comprising a concave bar spring having two ends and a downwardly and inwardly extending hook integrally formed on each end of said bar spring, said hooks adapted to engage the container flange when said bar spring is under tension,

a plurality of ribs on said side wall maintaining the cap member and clip in fixed angular relation wherein one edge of said bar spring is in alignment with said grooves,

an outwardly extending lip integral with said cap member normal to and opposite said bar spring edge, whereby an upward pressure exerted on said lip will break said cap member along said bar spring edge.

3. A closure according to claim 1 having a sealing disc in said cap member.

4. The combination of a container and a closure therefor comprising
 a container having a flanged neck opening,
 a brittle cup-shaped cap member fitting over said flange
 having a flat top wall and a downwardly extending
 circular side wall, said side wall being divided into
 two portions by diametrically opposed notches, 5
 a clip fitting over said cap member comprising a con-
 cave bar spring having two ends and a downwardly
 and inwardly extending hook integrally formed on
 each end of said bar spring, said hooks engaging
 said flange when said bar spring is under tension, 10
 a plurality of ribs on said side wall maintaining the
 cap member and clip in fixed angular relation where-
 in one edge of said bar spring is in alignment with
 said notches,
 an outwardly extending lip integral with said cap mem-
 ber

ber normal to and opposite said bar spring edge
 whereby an upward pressure on said lip will break
 said cap member along said bar spring edge.
